UNITED STATES PATENT OFFICE.

FRANK L. SESSIONS, OF LAKEWOOD, OHIO.

KNITTING-NEEDLE.

1,286,125.

Specification of Letters Patent. Patented Nov. 26, 1918.

Application filed November 27, 1917. Serial No. 204,241.

To all whom it may concern:

Be it known that I, FRANK L. SESSIONS, a citizen of the United States, residing at Lakewood, in the county of Cuyahoga, and 5 State of Ohio, have invented certain new and useful Improvements in Knitting-Needles, of which the following is a specification.

My invention relates to hand knitting needles, and has for its principal object the 10 provision of a new and improved needle for knitting either flat or tubular knitted articles. To accomplish the objects of my invention I provide a needle having a flexible work carrying or body portion terminating 15 at its ends in knitting points, the extreme ends of which are fashioned or shaped as are the points of the ordinary hand knitting needle.

In knitting with ordinary knitting needles 20 it is necessary when knitting flat work to employ two needles and to knit first off from the one, on which the work has been cast, on to the other, and then from the latter on to the former and so on, the work being 25 carried by one needle only when a row has been finished. At all other times the work is carried partly by one needle and partly by the other. For knitting tubular articles it is necessary that the work be carried by 30 three or more needles and that an extra needle be employed for knitting the work off from one of the work carrying needles. When the work is large, as when knitting a sweater, it has heretofore been necessary to 35 employ extremely long needles which it is comparatively difficult and tiresome to manipulate, especially if the work be heavy or bulky.

With my new and improved needle either 40 flat or tubular work may be knitted upon a single needle having one or two points, and the labor is much less tiresome and can be performed in less time and with less danger of mistakes being made than when knitting 45 with ordinary knitting needles.

My invention is clearly shown in the accompanying drawings in which:—

Figures 1, 2, 3, 4, and 5 are perspective views of one of my improved needles, the 50 different figures showing the approximate positions assumed by the points when knitting a stitch off from one point on to the other;

Figs. 6, 7, 8, 9, 10, 11, 12 and 13 are views 55 of needles embodying my invention but

made in various ways of various materials which will be further described;

Figs. 14 and 15 show a modification of my improvement incorporated in a needle having a single knitting point. 60

The needle shown in Figs. 1 to 5 inclusive has round knitting points, 1, 2, and a flat, flexible body portion, 3.

In all forms of needles embodying my invention it is desirable that the periphery 65 of the transverse section of the needle be constant throughout the entire length except at the extreme, pointed ends, in order that the stitches may slip readily from point to body portion and vice versa. It is also de- 70 sirable that the surface of the needle be smooth and slick throughout the entire length for the same reason. I have found hard rubber or celluloid needles having points of sufficient stiffness to properly pick 75 up and cast the stitches, and having flexible body portions to be satisfactory.

The flexible, body portion of the needle may be made of the same material as the 80 points, or it may be made of different material and secured to the points in any convenient and suitable way.

In Figs. 6 and 7 there is shown a needle which has points, 4, 5, secured in hollow 85 sockets, 6, 7, which are formed upon or secured to the flat body portion, 8. The points, 4, 5, may be secured in the sockets, 6, 7, in any suitable way such as by threading the shanks of the points where they enter the sockets or by simply making a snug fit of the shanks of the points in the sockets. The points may be permanently secured to the flexible body, or, by making the points removable, different lengths may be substituted to suit the nature of the work or the 90 convenience of the knitter. It will be understood that the points, 4, 5, may be made of any convenient material such as celluloid, rubber, ivory, steel or other material, and that the flexible, body portion, 8, and the 95 socket portion, 6, 7, may also be made of any suitable material.

In Figs. 8 and 9, there are shown the 100 knitting points, 10, 11, pivoted to the flexible, flat, body portion, 12. The flexible needle permits heavy work which may be carried by it to sag naturally into the lap of the knitter without being supported by the hands.

In Fig. 10 there is shown a needle having 110

points, 13, 14, secured to the ends of a round, tubular, flexible body member, 15. This flexible body member may be made of any suitable material. I have found that 5 soft rubber, provided with a smooth, slick surface can be used for this purpose. I have also found that tubes braided from cotton or silk thread and coated with varnish can be used in the manner shown in Fig. 10. 10 In Fig. 11 there is shown a needle having points, 16, 17, secured to the ends of a round, flexible, body portion, 18, which is composed of a stranded cable. I have found that a cable of this sort made of fine, metallic 15 wires can be used.

In Fig. 12 there is shown a needle having points 19, 20, made of the same kind of material as the body portion, 21. It is essential that the points be stiff enough to 20 properly pick up and cast the stitches. The point and body material may be celluloid, hard rubber, vegetable reed, metallic wire, or other substance.

In Fig. 13 there is shown a needle having 25 points, 22, 23, secured to a round, flexible, body portion, 24, made of braided strands or of a flexible core covered with a braided armor of fine metal wire, silk thread or any other suitable material.

30 Figs. 14 and 15 show a modification of my invention consisting of a needle having a single, round, knitting point, 25, and a flat, flexible, body portion, 26. It will be understood that the use of this needle is the same 35 as the use of the ordinary, single end, knitting needle which is made of stiff material, but does not have the flexible, body portion. The flexible, body portion, 25, bends down and out of the way of the hands and arms 40 of the knitter, and allows large work to rest easily in the lap without having to be supported by the hands. I do not limit myself to any particular construction of the flexible portion of my needle. Any suitable article 45 having the desired flexibility may be employed. I have also used flexible metallic tubing and flexible, metal armored wires. The chief requisites of the flexible portion 50 of my needle are that it have a smooth surface and that its transverse section have a periphery of substantially the same length throughout the length of the flexible portion and that this periphery be the same as that of the cross section of the cylindrical knitting points.

55 Referring again to Figs. 1 to 5 inclusive the manner of using my two point flexible knitting needle will be readily understood from the following explanation:—The 60 stitches, to any number desired, are first cast upon, say, point, 1, Fig. 1. They may be only a few, when for knitting narrow work, or they may be enough to practically fill the length of the needle except about a half 65 inch at each extreme end, when for knitting

wide, flat work or circular tubular work. After the required number of stitches have been cast upon point, 1, the yarn will lead off to the supply ball from the last stitch cast upon that point, in the same way it 70 does when the work has been cast upon an ordinary knitting needle. To knit flat work, point, 2, is used as illustrated in Figs. 1 to 5 inclusive, which shows the approximate consecutive positions assumed by that point 75 in knitting one stitch. Those skilled in the art of hand knitting will readily observe that these positions are the same as those assumed by the point of an ordinary knitting needle in knitting one stitch from another needle. 80

As the stitches are knitted off from point, 1, on to point, 2, the work will slip around the flexible body portion in a clock wise direction as viewed in Fig. 1. When all of 85 the stitches have been knitted on to point, 2, the points are reversed in position, and the work is next knit off from point, 2, on to point, 1, and so on until the desired size of the article has been formed. 90

In order to knit a circular tubular article, the stitches are cast on to point, 1, as before, until they substantially fill the length of the needle, but instead of starting to knit off from point, 1, to point, 2, as when knitting flat articles, the position of the points is reversed and the stitches are knit off from point, 2, on to point, 1, thus joining the ends of the first row of stitches cast upon the needle, and thereafter the knitting may be 100 continued in the same direction around and around the article until the desired length of the tube has been formed, or, the direction may be reversed at the end of any round of stitches to produce the ribs which are produced by reversing the direction of knitting on flat work. In fact, the direction of knitting may be reversed at any point of any round desired. 105

It will be evident to those skilled in the 110 art that the total length of my flexible needle need be only as great as that of either one of a pair of ordinary stiff needles used for knitting flat work of the same width. It will also be apparent that two or more of my 115 flexible needles may be used in the same manner that ordinary stiff needles are used in knitting and that any work which can be done with the ordinary stiff needles can be done with my flexible needles. 120

Many advantages accrue from the use of my invention, some of which have been herein mentioned and others of which will appear from its use by skilled knitters in knitting various articles. 125

Having thus described my invention, I claim:—

1. A knitting needle having a knitting point and a body flexible and inert throughout its length substantially as described. 130

2. A knitting needle having two knitting points and a body flexible and inert throughout its length substantially as described.
3. A knitting needle having a knitting point and a smooth, flat, inert body flexible throughout its length.
4. A knitting needle having a substantially stiff knitting end and a flat body portion, the flat body portion being disposed so as to be most flexible in the plane of the knitting.
5. A knitting needle having two stiff knitting ends and a flexible body portion, said body portion being more flexible in the plane of the knitting ends than in other directions.
6. A knitting needle having a stiff knitting end and a body flexible in one plane but stiff in a direction transverse to the plane of its flexibility, the greater flexibility of the body in one plane being due to the 20 shape of its cross section.
7. A knitting needle having a substantially round knitting end and a flat body portion, the girth of the cross section of the body portion being substantially the 25 same as the girth of the cross section of the knitting end.

In testimony whereof I affix my signature in the presence of two witnesses.

FRANK L. SESSIONS.
